UNITED STATES PATENT OFFICE.

GEORGE W. REAM, OF CANTON, OHIO, ASSIGNOR TO THE BUCHER & GIBBS PLOW COMPANY, OF SAME PLACE.

DESIGN FOR A LAND-ROLLER.

SPECIFICATION forming part of Design No. 29,476, dated October 11, 1898.

Application filed September 15, 1898. Serial No. 691,043. Term of patent 14 years.

To all whom it may concern:

Be it known that I, GEORGE W. REAM, a citizen of the United States, residing at Canton, county of Stark, State of Ohio, have invented and produced a new and original Design for Land-Rollers, of which the following is a specification, reference being had to the accompanying drawings, in which—

Figure 1 is an end elevation; Fig. 2, a front elevation, and Fig. 3 a section on line xx of Fig. 2.

As shown in the drawings, the leading or material feature of the design consists in the shape and configuration of the parts, as seen in end and side elevation. These leading features consist in an end ring or casting having a corrugated or fluted periphery a , with a hub b , and spokes c radiating between

the hub and the rim of the end rings. The central ring is similar in shape to the end rings, except that it has a series of openings through its rim, as at d , and these openings contain bars of T shape. These bars extend between the rings, as shown in Fig. 2. Rods e extend between the end rings, passing through the center.

What I claim is—

The design for a land-roller herein shown and described.

In testimony whereof I affix my signature in presence of two witnesses.

GEORGE W. REAM.

Witnesses:

W. H. CAVNAH,
GEO. W. JAHN.
